UNITED STATES PATENT OFFICE.

ALFRED ORLIK, OF NEW YORK, N. Y.

DESIGN FOR A TOBACCO PIPE.

Application filed November 21, 1925. Serial No. 15,488. Term of patent 3½ years.

To all whom it may concern:

Be it known that I, ALFRED ORLIK, a citizen of the United States, residing in the borough of Manhattan, city, county, and State of New York, have invented a new, original, and ornamental Design for Tobacco Pipes, of which the following is a specification, reference being had to the accompanying drawing, forming part thereof.

Fig. 1 is a top view;

Fig. 2, a side elevation; and

Fig. 3, a view of the under side of a tobacco pipe, showing my new design.

I claim:—

The ornamental design for a tobacco pipe, as shown.

ALFRED ORLIK.
